(Cl. D92—1)

FIG. 1

FIG. 2

Fig. 1 is a fragmentary plan view of a double-faced tufted fabric embodying my new design.

Fig. 2 is a sectional view of the fabric taken as indicated by the angled arrows II—II in Fig. 1.

The design of Fig. 1 is repeated on both sides of the fabric, as indicated in Figure 2.

I claim:

The ornamental design for a double-faced tufted fabric, as shown and described.
